CLAIM

The ornamental design for a flow meter for bio-sensor, as shown and described.

DESCRIPTION

FIG. 1 is a front view of a flow meter for a bio-sensor of a new design;

FIG. 2 is a back view thereof;

FIG. 3 is a left side view thereof;

FIG. 4 is a right side view thereof;

FIG. 5 is a plan view thereof;

FIG. 6 is a bottom view thereof; and,

FIG. 7 is an assembling view showing a condition wherein the flow meter is incorporated in a sensing apparatus.
